United States Patent

Des. 234,897
Patented Apr. 15, 1975

234,897

SHEET

Grace Mazzagatti, Nederland, Tex.
(Rte. 4, Box 68-D, Beaumont, Tex. 77705)

Filed June 8, 1973, Ser. No. 368,260

Term of patent 14 years

Int. Cl. D6—13

U.S. Cl. D6—264

The figure is a plan view of a sheet showing my new design with the decorative top portion folded down over the plain portion, the sheet is shown broken away for convenience of illustration.

I claim:

The ornamental design for a sheet, substantially as shown and described.

References Cited

UNITED STATES PATENTS

D. 129,904 10/1941 Marghab _____ D6—264
D. 212,204 9/1968 August _____ D6—264

LOIS S. LANIER, Primary Examiner